UNITED STATES PATENT OFFICE.

PRESTON KYLE AND CHARLES LONG, OF COAL BLUFF, INDIANA.

COMBINED SWITCH AND SIGNAL.

No. 920,348.

Specification of Letters Patent.

Patented May 4, 1909.

Application filed September 17, 1908. Serial No. 453,560.

To all whom it may concern:

Be it known that we, PRESTON KYLE and CHARLES LONG, citizens of the United States, residing at Coal Bluff, in the county of Vigo 5 and State of Indiana, have invented certain new and useful Improvements in a Combined Switch and Signal; and we do declare the following to be a full, clear, and exact description of the invention, such as will enable 10 others skilled in the art to which it appertains to make and use the same.

This invention relates to improvements in manually operated railroad switches and signals and comprises the construction of a 15 railroad switch and signal provided with a vertically operated lever.

One of the objects of the invention is the construction of a simple switch mechanism comprising a stand, a signal operatively 20 mounted on the stand and a lever mechanism arranged to be vertically operated and simultaneously throw a switch and operate the signal.

With this and other objects in view, the 25 invention consists of certain novel features of construction, combination and arrangement of parts as will be more fully described and particularly pointed out in the appended claims.

30 Figure 1 is a side elevation of our improved switch showing the operating lever in its normal position; Fig. 2 is a similar view showing the operating lever depressed; Fig. 3 is an end elevation; and Fig. 4 is a horizontal section.

In the drawings, numerals 1 and 2 designate main rails and 3 and 4 designate switch rails. The main rail 2 and the switch rail 3 are connected by a slidable bar 5 which is 40 slidable between guide pieces 6 and 7. The slidable bar 5 is formed with an end slot 8 and is connected with a link 9. The link 9 is slightly curved upwardly at one of its ends and is slotted at its curved end to receive a 45 crank lever 10. The lever 10 is pivotally mounted upon a stand 11 provided with an off-set 12 and connects at its upper end with a link 13, which link is pivotally connected at its upper end with a lever 14 which is 50 pivotally mounted on the stand 11 by means of an upper off-set 15. The lever 14 is formed with a body slot 16 through which a rack 17 extends, said lever being provided with a suitable clutch 18 for engaging with 55 said rack.

A signal carrying bar 19 is movably

mounted on the stand 11 by means of apertured lugs 20 and 21 formed on said stand and said bar carries a suitable signal 22 on its upper end. The signal carrying bar 19 is 60 formed with a lateral lug 23 which is connected with a link 24 having connections with the switch operating link 9.

Should it be desired, the clutch 18 may be dispensed with and the rack 17 provided with 65 apertures and a pin arranged to extend through the apertures for locking the lever 14 on said rack so as to hold the switch in a closed or open position. When it is desired to throw a switch, the lever 14 is depressed. 70 This operation will raise the link 13 and simultaneously bring rail 3 into engagement with rail 1 and operate the signal carrying bar 19.

Our improved switch and signal mechanism provides simple means for operating a switch and securing the same in a fixed position by the application of vertically applied pressure. 75

From the foregoing description, taken in 80 connection with the accompanying drawings, the construction and operation of the invention will be readily understood without requiring a more extended explanation.

Various changes in the form, proportion 85 and the minor details can be resorted to without departing from the principle or sacrificing any of the advantages of this invention as defined in the appended claims.

Having thus described and ascertained the 90 nature of our invention, what we claim as new and desire to secure by Letters-Patent is:

1. In combination with switch rails, a bar for moving a part of the rails, a link connected to the bar, a crank lever for operating the link, a link for operating the crank lever, a lever for operating the link last mentioned, a stand pivotally supporting the operating means, a rack arranged to extend through the lever and supported on the stand, a vertical signal carrying bar operatively supported on the stand, and a link having connections with the operating link for operating the signal carrying bar. 95 100 105

2. The combination with switch rails, of a stand formed with an off-set, a lever pivotally supported on the off-set and the stand, a link connected to the lever, a second lever connected to the link, a link having connections with a part of the switch rails connected to the second lever, a signal carrying bar op- 110

eratively supported on the stand, and a link connected to the signal carrying bar connected to the last mentioned link.

3. In a switch, a signal operating device, a supporting stand, a transversely disposed switch throwing bar connected with the switch tongues, an operating lever pivoted on said stand, a vertical signal carrying rod provided near its lower end with a lateral off-set 10 mounted upon said stand, operative connections including a horizontal link and vertical links between the operating lever and the switch throwing bar, and a second link between said horizontal link and the off-set of

the signal carrying rod for turning the latter 15 when the operating lever is depressed to throw the switch.

In testimony whereof we have hereunto set our hands in presence of two subscribing witnesses.

PRESTON ^{his} X KYLE.
CHARLES LONG.
